UNITED STATES PATENT OFFICE.

THOMAS H. PREST, OF KANSAS CITY, MISSOURI, ASSIGNOR TO THE PREST HEATING COMPANY, OF KANSAS CITY, MISSOURI, A CORPORATION OF MISSOURI.

HEATING-FURNACE.

SPECIFICATION forming part of Letters Patent No. 687,062, dated November 19, 1901.

Application filed April 9, 1897. Serial No. 631,472. (No model.)

To all whom it may concern:

Be it known that I, THOMAS H. PREST, a citizen of the United States, residing in Kansas City, in the county of Jackson and State 5 of Missouri, have invented certain new and useful Improvements in Heating-Furnaces, of which the following is a specification, reference being had therein to the accompanying drawings.

10 My invention relates to improvements in heating-furnaces.

The object of my invention is to provide a heating-furnace in which the heated products resulting from the combustion of the fuel 15 used are equally distributed throughout the radiating mechanism, thus making the wear of the different parts of such mechanism equal and at the same time affording an economical and efficient heating apparatus.

20 My invention has for its object also the providing of an apparatus that may be readily adapted to varying conditions that may occur in setting up the furnace.

My invention has for its object still further 25 the providing of an apparatus in which a series of radially-disposed radiating-pipes of equal length and capacity are connected at one end with the combustion-chamber and at their other ends are connected with a common 30 discharge-chamber, which in turn has connected to it the main smoke-pipe.

My invention also provides a novel construction by means of which the main smoke-pipe may be connected with the discharge-chamber in various positions.

35 In my invention are also included certain novel and useful features of construction hereinafter fully described and claimed.

In the accompanying drawings, which illustrate my invention, Figure 1 represents a 40 vertical sectional view of a furnace constructed in accordance with the principles of my invention. Fig. 2 represents a transverse horizontal sectional view taken on the 45 dotted line II II of Fig. 1 and looking in the direction indicated by the arrows which are adjacent to the characters which indicate the said dotted line. Fig. 3 represents a perspective view of the common receiving-chamber 50 having the cap secured to the lower end thereof and the smoke-pipe elbow above the chamber, but disconnected therefrom. In

this view are also shown the upper ends of the radiating-pipes. Fig. 4 represents an elevation view of the vertically-movable inner collar which encircles the smoke-pipe, a portion of the casing being shown and also showing the smoke-pipe in cross-section.

Similar numerals of reference indicate similar parts throughout the several views.

1 indicates the casing, which is of the ordinary form and constructed preferably of sheet metal; 2, the canopy or covering for the casing and from which extend the hot-air pipes 3.

4 indicates the front of the furnace, which may be of any suitable material or shape. Cast or wrought iron is generally preferred for the material from which to construct the front of the furnace.

5 designates the ash-pit, preferably of cast-iron, closed upon all sides and provided in its front with a rectangular door-opening and in its top plate with a circular opening, by means of which connection is established 75 between the fire-pot and the ash-pit. The bottom plate 6 of the ash-pit has its under side flush with the lower edge of the front of the furnace and also lying in the same horizontal plane as the lower side of the base-ring 80

7. The ash-pit bottom near its forward end inclines upwardly toward the bottom side of the door-opening, so as to permit the easy extraction of the ashes. The rear end of the ash-pit is preferably semicircular in form and 85 has secured to it at its lower end a flange 8, which extends from one side of the furnace-front around the ash-pit to the other side thereof. The flange 8 inclines upwardly from the ash-pit and then outwardly horizontally 90

and has secured to it the inner ends of several arms 9, which extend inwardly from the upper end of the base-ring 7. Resting upon the top plate of the ash-pit is the annular fire-pot 10, the opening through which is in 95 line with the opening in the top of the ash-pit. Resting upon the upper edge of the fire-pot 10 is a hollow annular cast ring 11, the lower side of which is provided with a vertical annular flange 12, adapted to engage with a 100

groove in the upper edge of the fire-pot to prevent lateral shifting of the ring. The upper side of the ring 11 is provided with an annular groove adapted to receive a vertical

annular flange 13 around the periphery of an opening in the bottom of the combustion-chamber 14.

The general form of the combustion-chamber is that of an upright hollow cylinder provided at its front side with a rectangular feed-neck 15, which extends through a rectangular opening in the furnace-front 4. Around the feed-neck 15 at its forward end is an external flange 16, to which is secured the feed-door frame, comprising a vertical flat plate 17, having an opening therethrough corresponding in size and position to the opening in the feed-neck. Hinged to the plate 17 upon one side is the feed-door 18, adapted when closed to close the opening in the feed-neck.

Located upon the top of the combustion-chamber at equal distances apart are a series of upwardly-extending inwardly-inclined radiator-pipes 19 radially disposed, the lower end of each of which pipes is located between two concentric vertical flanges 20 and 21, respectively, upon the upper side of the combustion-chamber and encircling an opening 22 therethrough. The upper inner end of each of the pipes 19 is connected with a vertical hollow drum or receiving-chamber 23, into which pass the products of combustion from each of the radiator-pipes 19. The common discharge or smoke pipe 24 is horizontally disposed and extends through an opening in the casing 1. The inner end of the smoke-pipe 24 is curved, so as to form a right-angled elbow, the inner end of which is provided with a horizontal external flange 25 and a vertical groove 26, adapted to fit over either the upper or lower end of the receiving-chamber 23, which is provided at its upper end with a vertical internal flange 27, which is concentric with the body of the combustion-chamber and forms a groove therewith for the reception of the inner one of two concentric flanges 28 and 29, respectively, located upon the under side of a horizontal cap-plate 30, adapted to close the upper end of the receiving-chamber. The cap-plate 30 is provided with a series of vertical openings, through which extend the vertical bolts 31, which have their lower ends secured in vertical openings in the flange 25 of the smoke-pipe. The construction of the parts is such that the smoke-pipe may be located in the position shown in solid lines in Fig. 1, with the inner end secured to the lower end of the receiving-chamber and the cap 30 secured to the upper end thereof, or, if desired, their respective positions may be reversed, as indicated by the dotted lines in the same figure.

Encircling the smoke-pipe 24 outside the casing is a collar 32, secured by means of bolts 33, which pass through openings in the casing to a collar 34, which encircles the smoke-pipe 24 inside the casing. The openings in the casing which admit the bolts 33 are vertically elongated, so as to permit vertical movement of the collars. The opening provided in the casing for the admission of

the smoke-pipe is large enough to permit of vertical movement of the smoke-pipe 24. In furnaces as ordinarily constructed the vertical lifting of the smoke-pipe 24, caused by the warping of the castings of the fire-pot or of the combustion-chamber, either raises the casing from its bearings in the base ring or plate, or if the casing is secured rigidly to the base-plate the opening through which the smoke-pipe passes will be enlarged, permitting hot air to pass from the interior of the casing into the room occupied by the furnace. To avoid either of these two objections, I have provided the smoke-pipe with a vertically-movable bearing in the casing, as described.

Extending vertically through the combustion-chamber are a series of hot-air flues 35, which are disposed around in a circle concentric with but of larger diameter than the ring 11. The function of these hot-air flues is to heat the air passing upward therethrough. Each of the said flues is fitted at its upper and lower ends in vertical openings provided in the top and bottom plates, respectively, of the combustion-chamber. The lower end of each of the said flues 35 is provided with an annular flange 36, disposed in an oblique plane parallel to the bottom plate of the combustion-chamber upon which it rests. The upper end of each of the said hot-air flues is provided with an external horizontal annular flange 37, the upper side of which is provided with two seats which rest in corresponding recesses annular in shape and concentric with the opening in the top plate of the combustion-chamber, through which the flue extends, and located in the under side of the said top plate. Around each flue-opening in the said top plate of the combustion-chamber upon the upper side thereof is a vertical annular flange 38. A space is provided between the said flange 38 and the portion of the flue 35 which is above the top of the combustion-chamber, in which stove putty is placed for the purpose of sealing the joint against the escape of smoke or gas therethrough.

In setting up the furnace the smoke-pipe 24 may be secured upon the end of the chamber 23 in any of the positions between the radiator-pipes, as shown in dotted lines between the radiator-pipes 19 in Fig. 2, after which the bolts 31 are inserted through the openings provided therefor in the cap-plate 30 and the flange 25 of the smoke-pipe and secured therein. The opening in the casing for the admission of the smoke-pipe therethrough should be made in the proper location in the casing suiting the chosen position for the smoke-pipe. By this construction one is enabled to pipe directly to the flue in the building from the smoke-pipe. If the draft of the chimney with which the smoke-pipe is to be connected is not strong, then the positions of the smoke-pipe and the cap 30 may be reversed from that shown in solid lines in Fig. 1 to the position indicated by dotted lines

- in the same figure, as hereinbefore described. Where the draft is good, it is preferable to use the smoke-pipe in the lower position, as more economy in the use of fuel is thus attained, as well as increased heating capacity. With the radiator-pipes 19 of equal capacity and symmetrically arranged upon the combustion-chamber at equal distances apart and connected to a common receiving-chamber centrally located, as shown, the products of combustion are equally divided between the several radiator-pipes, and each pipe thus has a heating effect upon the incoming air to be heated equal to any of the other radiator-pipes, making a very efficient heating apparatus, at the same time distributing the heat equally throughout the furnace and preventing undue destruction by heat of any one part of the fire-pot or combustion-chamber.
- 20 My invention is subjective to many modifications without departing from its spirit. Having thus described my invention, what I claim, and desire to secure by Letters Patent, is—
- 25 1. In a heating-furnace, the combination with a combustion-chamber, of a cylindrical receiving-chamber, a plurality of radiator-pipes connecting the combustion-chamber with the receiving-chamber, a cap adapted to be secured to either end of the receiving-chamber, a smoke-pipe adapted to either end of the receiving-chamber, and means for securing the said cap and the said smoke-pipe to the receiving-chamber, substantially as described.
- 30 2. In a heating-furnace, the combination with a combustion-chamber, of a tubular receiving-chamber, radiator-pipes connecting the combustion and the receiving chambers, a cap for covering either end of the receiving-chamber, a smoke-pipe covering the opposite end of the said chamber, and one or more bolts connecting the cap and the smoke-pipe, substantially as described.
- 35 3. In a heating-furnace, the combination with a combustion-chamber, of a tubular receiving-chamber, radiator-pipes connecting the said two chambers, a cap provided with a groove adapted to receive one end of the receiving-chamber, a smoke-pipe provided with a groove adapted to receive the other end of the receiving-chamber, and means for securing the said smoke-pipe and the cap interchangeably at either end the receiving-chamber, substantially as described.
- 40 4. In a heating-furnace, the combination with a tubular combustion-chamber provided in one end with a series of openings disposed equidistant from each other and equidistant from the axial center of the combustion-chamber, of a tubular receiving-chamber having the same axial center as the combustion-chamber, and provided in its periphery with a series of openings corresponding in number to
- 45 the openings in the end of the combustion-chamber, radiator-pipes connecting the said openings in the two chambers, a cap adapted

to be secured at either end of the receiving-chamber and a smoke-pipe adapted to be connected with the other end of the receiving-chamber, substantially as described. 70

5. In a heating-furnace, the combination with the vertical tubular receiving-chamber provided with peripheral openings therethrough and provided with means for closing either end, of the horizontal smoke-pipe having its curved inner end adapted to be secured to either end of the receiving-chamber, substantially as described. 75

6. In a heating-furnace, the combination with the tubular receiving-chamber provided with peripheral inlet-openings, of a cap adapted to be secured to and close either end of the said receiving-chamber, a smoke-pipe secured to the open end of the receiving-chamber, substantially as described. 80

7. In a heating-furnace, the combination with the tubular receiving-chamber provided with peripheral inlet-openings, of a cap provided with a groove adapted to receive either end of the said tubular chamber, a smoke-pipe provided with a groove adapted to receive either end of the said tubular chamber, and means for securing the cap and pipe to the said chamber, substantially as described. 90

8. In a heating-furnace, the combination with a combustion-chamber, of a receiving-chamber, a smoke-pipe, means by which the smoke-pipe may be connected to the upper or lower end of the receiving-chamber, means for closing the opposite end thereof, and a radiator-pipe connecting the combustion-chamber with the receiving-chamber, substantially as described. 100

9. In a heating-furnace, the combination with a combustion-chamber, of a receiving-chamber provided with two discharge-openings, a smoke-pipe, means by which the smoke-pipe may be connected to either of the two of said openings, means for closing the other of said openings, and radiator-pipes connecting the receiving-chamber with the combustion-chamber, substantially as described. 105

10. In a heating-furnace, the combination with a combustion-chamber, of a receiving-chamber, a discharge-pipe, means by which the said discharge-pipe may be connected to the upper or the lower end of the receiving-chamber, means for closing the opposite end thereof, and a series of radially-disposed radiator-pipes located at equal distances apart and of equal lengths and connected at their lower ends to the combustion-chamber and inclining upwardly and inwardly therefrom to the receiving-chamber to the vertical sides 110 of which the radiator-pipes are connected, substantially as described. 120

In testimony whereof I affix my signature in presence of two witnesses.
